(57) **CLAIM**

The ornamental design for an automobile as shown and described.

DESCRIPTION

The patent or application file contains at least one drawing executed in color. Copies of this patent or patent application publication with color drawing(s) will be provided by the Office upon request and payment of the necessary fee.

1. Automobile
  - 1.1 is a front elevation view of an automobile, showing our new design;
  - 1.2 is a rear elevation view thereof;
  - 1.3 is a right side elevation view thereof;
  - 1.4 is a left side elevation view thereof;
  - 1.5 is a top plan view thereof;
  - 1.6 is a front, top, right side perspective view thereof; and
  - 1.7 is a rear, top, right side perspective view thereof.
  - 1.8 is an enlarged view of Figure 1.1.
  - 1.9 is an enlarged view of Figure 1.2.
  - 1.10 is an enlarged view of Figure 1.6.
- The broken lines in the drawings surround portions of the automobile that form no part of the claimed design. The solid line square in Figure 1.6, labeled A, is for the purpose of illustrating the enlarged view and forms no part of the claimed design.

1 Claim, 10 Drawing Sheets
